UNITED STATES PATENT OFFICE.

HENRY A. WILBUR, OF CAMBRIDGE, ASSIGNOR OF ONE-HALF TO FRANK W. LOWE, OF BOSTON, MASSACHUSETTS.

MORTISING-MACHINE.

SPECIFICATION forming part of Letters Patent No. 293,607, dated February 12, 1884.

Application filed May 22, 1883. (No model.)

To all whom it may concern:

Be it known that I, HENRY A. WILBUR, a citizen of the United States, residing at Cambridge, in the county of Middlesex and State of Massachusetts, have invented a new and useful Improvement in Window-Pulley Mortising-Machines, of which the following is a specification.

The object of my invention is to produce a mortising-machine capable of cutting slots in window-sash frames for the reception of the pulleys, and also cutting recesses at each end of said slots for the reception of the end flanges of said pulleys.

The invention consists in a feed-table for holding the material to be operated upon, which table is capable of being moved in both a longitudinal and transverse direction, by means of which the material is fed to two compound revolving cutters, so that the cutters will first cut slots for the reception of the pulleys and a recess for the side flanges, then be partially withdrawn, so that the inner or smaller cutters will cut recesses at each end of the slots for the reception of the end flanges of the pulleys. When square-end flanged pulleys are to be inserted, the slots for the main body of the pulleys are first cut, then the cutters are changed and the recesses for the flanges cut.

In the accompanying drawings, Figure 1 represents a front view of a machine embodying my invention. Fig. 2 is a plan or top view of the same. Fig. 3 is an end view. Figs. 4 and 5 represent pieces of material with slots and recesses cut therein.

A is the main frame of the machine.

B is a sliding table, the edges of which are wedge-shaped, and fit into corresponding guides, C, secured to the main frame. The sliding table B is provided with standards D, which carry the cutter-spindles E E'. The upper one, E, is adjustable by means of screws F. A reciprocating movement is imparted to the table B from an eccentric block, H, through connecting-rod G.

I is a shaft which carries the eccentric block, and also a pulley, J, which is driven by belt K from a pulley, L, on the main shaft M, which latter also carries the fast and loose pulleys N and O, around which pass

the belts P P', that drive the cutter-spindles E E'.

E' is an idler for taking up any slack in the belt P', caused by the adjustment of the upper spindle, E'.

Q Q are brackets secured to the side of the frame A, and each provided on their inner sides with a tongue, on which slides the plate R, having on its under side a nut, r, through which passes a screw, S, one end of which latter is secured (but so as to revolve freely) to the main frame A, the other end being provided with the hand-wheel T. On the screw S are placed check-nuts s s', which can be adjusted so as to regulate the travel of the plate R.

In the upper surface of the plate R is cut a recess, with beveled edges, in which the lower portion of a plate, U, fits, so as to slide freely, motion being communicated to the plate U from the hand-lever V through rod u.

W is an adjustable stop for regulating the travel of the plate U, which stop is fixed to the plate U, and is provided at its outer end with a lug, through which passes a screw, W', secured to the plate R.

On the screw W' are two nuts, w w', one on each side of the lug or stop W, so that when the plate U is pushed in one direction the stop W will strike against the nut w, and when pushed in the opposite direction it will strike against the nut w'.

x is a pin for holding the plate U in position on plate R, when it is not required to give the plate U an independent movement.

X X are standards on the plate U, against which the material to be operated is clamped by means of a clamp, Y, which is carried by a pillar on the plate Z, secured to the plate U by means of bolts passing through slots, so that the plate Z can be adjusted according to the thickness of the material being operated upon.

To one of the standards X are secured the gages a b. The gage a is for regulating the distance from the end that the hole is to be cut, and b for regulating the distance from the edge of the material.

For regulating the depth of the cut at each end of the slot for the reception of the flanges of the pulleys, I fix to the plate R a short bar, c, and to the bracket Q the adjustable slide e,

to which is pivoted a short arm, *d*, having a recess to fit over the bar *c*.

The operation is as follows: The stops and gages are first adjusted according to the position and length of slots to be cut, and the clamp *Y* and nuts *s* *s'* adjusted according to the thickness of the material to be operated upon. A piece of material is then placed on the machine so that its end will bear against the gage *a* and its side rest on the gage *b*. The material is then firmly held in position by turning the clamp *Y*, which presses it against the standards *X* *X*. Thus far the operation is the same in all cases, and I will now first describe the operation for cutting the slots and recesses, as shown in Fig. 4. By turning the hand-wheel *T* the material is fed toward the cutters until the nut *r* comes in contact with the check-nuts *s*, when the material will have been bored through the desired depth. At the same time the reciprocating motion of the sliding table *B* will have carried the cutters backward and forward and cut the hole and recess around same the desired length. The arm *d* is now thrown down onto the bar *c*, and the hand-wheel *T* turned in the reverse direction until the bar *c* comes under the notch in the arm *d*, when it will drop over the bar *c* and hold it in position. The pin *x* is now removed and the hand-lever *V* operated, which carries the plate *U* backward and forward, so that the inner or smaller cutter will cut a recess at each end of the slot already cut. The arm *d* is then raised, and the hand-wheel *T* turned until the nut *r* strikes against the check-nut *s'*. The clamp *Y* is then turned and the material released.

I will now describe the operation when it is required to cut for a pulley with a flange, as

shown in Fig. 5, or for a square-end pulley, as shown in dotted lines. In this case I employ, first, only the cutter for cutting the slots, which being done as above described, I withdraw the material and place on the spindles cutters of larger diameter, and feed the material toward them until they have cut the required depth. The lever *V* is then operated, and the length of the recess is regulated by the travel given to the plate *U*, as above described, and a recess, of the shape shown in Fig. 5, will be cut, which is suitable for round-end pulleys, but also suitable for square-end pulleys, only requiring the corners (shown in dotted lines) to be cut out with a chisel.

What I claim as my invention is—

1. In a mortising-machine, the combination of the plate *R*, sliding in brackets *Q* *Q*, and operated by the screw *S*, through the nut *r* on plate *R*, and the sliding plate *U*, operated by the lever *V* and connecting-rod *u*, the screw *W*, adjustable stop *W*, and check-nuts *w* *w'*, all as shown, and for the purpose set forth.

2. In a mortising-machine, the combination of the sliding plate *R*, the bar *c*, fixed to the plate *R*, the adjustable slide *e*, attached to the bracket *Q*, and the arm *d*, pivoted to the slide *e*, and provided with a recess fitting over the bar *c*, for the purpose of regulating the depth of cut at each end of the mortise for the reception of the pulley-flanges, as set forth.

In testimony whereof I have signed my name to this specification in the presence of two subscribing witnesses.

HENRY A. WILBUR.
